United States Patent Office

Des. 216,954
Patented Mar. 24, 1970

216,954

MULTIPLE UNIT HOUSING STRUCTURE

Louis J. Jenn, 4917 Laurel Circle,
Indianapolis, Ind. 46226

Filed July 15, 1968, Ser. No. 12,739

Term of patent 14 years

Int. Cl. D25—04

U.S. Cl. D13—1

Fig. 1.

Fig. 2.

FIG. 3.

FIG. 4.

FIGURE 1 is a prospective view of a multiple unit housing structure according to my design.

FIGURE 2 is a side elevation of the structure shown in FIGURE 1.

FIGURE 3 is a prospective view of a two story multiple unit housing structure according to my design.

FIGURE 4 is a side elevation of the structure shown in FIGURE 3.

The sides of the structure not shown, opposite those shown in FIGURE 1 are like the sides shown in FIGURE 1.

I claim:

The ornamental design for a multiple unit housing structure, as shown and described.
